UNITED STATES PATENT OFFICE

HENRY E. THOMPSON, OF NEWARK, NEW JERSEY, ASSIGNOR TO THE PEERLESS AWNING HARDWARE CO., INC., A CORPORATION OF NEW JERSEY

AWNNG ACTUATOR

Application filed October 27, 1926. Serial No. 144,414.

This invention relates to reels and more particularly to such winding devices as are adapted to awnings, shades and the like.

One of the objects of the invention is to provide means whereby awnings may be conveniently raised or lowered from the inside of a building and so save an operator from the necessity of exposure to weather conditions.

Another object is in the provision of devices having means to secure an awning at a partially opened or closed position.

A further aim is to produce means whereby a shade or similar weather protector may be held in a positively rigid and taut position, thus eliminating creaking, flapping and other annoying sounds caused by the wind.

These and other objects, which will become apparent as the description progresses, are accomplished by the novel construction, incorporation and disposition of elements hereinafter recited and exemplified in the associated illustrations, forming a material portion of this disclosure, and in which:—

Figure 1 is a front elevation view looking at the inner side of a conventional type of window provided with an awning, illustrating an application of the invention.

Figure 2 is a vertical sectional view taken on line 2—2 of Figure 1.

Figure 3 is an enlarged fragmentary view of the window shown in Figure 1 showing the reel support attached to a screen frame.

Figure 4 is a further enlarged sectional view taken on line 4—4 of Figure 3.

Figures 5 and 6 are front and sectional views respectively of a modified form of footing for the support bracket.

Figure 7 is a front view similar to Figure 1 but showing a single control reel.

Figure 8 is an enlarged fragmentary front view of the reel bracket as used in connection with the device shown in Figure 7.

Figure 9 is a transverse sectional view taken on line 9—9 of Figure 8.

Figure 10 is a front elevational view of a further modified form of reel bracket.

Figure 11 is a longitudinal sectional view taken on line 11—11 of Figure 10.

To clearly illustrate an application of the invention the wall of a building is designated by the numeral 15, the same containing an opening in which is set a window frame 16 containing sliding sashes 17, outside of which is a screen 18 contained in a rectangular frame 19.

An awning 20 of conventional triangular shape is supported by cords 21 running over pulley 22 at the top of the window from over which the awning is disposed, these cords being arranged to raise, lower and control the awning, adjustments being effected by a reel over which the cords are wound.

In the present case a reel 23 of novel form is employed, the same consisting of a pair of concavo-convex discs 24 arranged with their concave sides facing one another and rigid on a spindle 25 reaching through the screen towards the inner side of the window and formed to present two reduced rectangular stepped portions 26 and 27.

The main cylindrical portion of the spindle 25 is revolvably mounted in the hub 28 of a support bracket, this hub having a reduced shouldered portion 29 fitting an appropriate opening in the screen 18—by which is meant the ordinary woven wire netting commonly employed—and engaging the outer convex surface of the adjacent reel side.

As shown in Figures 1 to 4 the opposite end of the hub has an integral arm 30 divided into branches 31 directed at right angles and formed with feet 32 adapted to extend outward and over the corresponding angular corner members of the screen frame 19.

These feet may be rigidly secured to the frame members by rivets, if of metal or by screws, as shown if the frame be made of wood.

In place of the feet overlying the frame members as described, shorter feet 32' may be used to secure the bracket to the inner surfaces of the frame as shown in Figures 5 and 6; in all cases it is to be noted that the bracket is not only rigidly supported but the frame elements 19 are held firmly in fixed relation.

Mounted on the larger, inner squared portion 26 of the reel spindle is a ratchet wheel 33 its teeth being engaged by a pawl 34 pivoted at 35 on an extension 36 of the bracket hub 28 and formed on the opposite end of the pawl is a finger hold 37 having a stop 38 below it and bent at an angle to contact with the hub, the arrangement being such as to normally maintain the pawl free of the ratchet except when the reel is under stress.

Engageable with the outer squared portion 27 of the reel spindle is a hub 39 from which extends a lever 40, bent to avoid interference with the sash and provided with a handle 41 by which the reel may be rotated manually in either direction, raising or lowering the screen as desired, or holding it in adjustment by engaging the pawl 34.

In the modification illustrated in Figures 7 to 9, a reel structure of identical construction is employed but the same is furnished with a single standard, its footing 43 being disposed centrally of the screen frame 19 on its lowest member.

Figures 10 and 11 show a reel support removably engaged with a fixed bracket consisting of a flat plate 50 having spaced overlying ends 51 one of which may be provided with a set screw 52 and one of the longitudinal edges are turned to provide a flange 53, the structure constituting in effect a socket fixed to one of the frame members 19.

Slidably engageable in the socket are a pair of flat outstanding flanges 54, offset from a base 55 having a semi-circular hollow casing 56 over which is a circular cover plate 57.

Mounted in the base 55 and plate 57, axially of the casing 56, is a spindle 58 having an enlarged head 59 disposed in the recess below the base 55, and fixed on the spindle 58 is a reel 60 or sheave wheel having concave inner sides as before described.

Fixed on the outer extending portion of the spindle 58 is a ratchet wheel 61 and outwardly therebeyond is the hub of a handled lever 62 by which the reel may be rotated.

In this device a pair of pawls 62, 63 are pivoted in spaced relation on the plate 57 to engage the teeth of the ratchet, the outer ends of the pawls being connected by a link 64 having a knob 65 by which both pawls may be manipulated in unison.

The advantage of the pair of pawls is that a double locking means is attained tending to safety, and obviously the convenience and ease in removing the reel, together with its bracket, intact from a supporting socket, is an advantage.

While certain preferred embodiments of this device have been shown and described, it will be understood that changes in the

form, arrangements, proportions, sizes and details thereof may be made without departing from the scope of the invention as defined in the appended claims.

Having thus described my invention, what I claim as new and desire to secure by Letters Patent, is:—

1. In an awning actuator for openings having a frame screen, a bracket having a hub extending through the screen from the inner side thereof, a spindle in said bracket having a square inner end, a handle engageable on the squared end for manually rotating said spindle, a pulley on said spindle on which to reel the awning cord, and a support for said bracket having two radial arms extended at right angles to engage the screen frame at its inner side adjacent the corners whereby to hold the frame rigid.

2. In an awning actuator for openings having a fixed frame screen, a bracket having a hub extending through the screen, a spindle in said bracket, means for manually rotating said spindle, said means being removable, a pulley on said spindle on which to reel the awning cord, a ratchet wheel fixed on said spindle, a pair of pivoted pawls engageable with said wheel, a pivoted connection between said dogs to cause simultaneous action, and integral arms on said bracket fixed to the bottom and side elements of one corner of the screen frame at the inner side thereof.

3. In an awning actuator for a fixed screen carrying frame having an opening therethrough, a bracket fastened to the inner sides of said frame and having a hub extending through the opening in the screen at one corner thereof, a spindle revoluble in said hub, a pulley on the outer end of said spindle for connection with one end of an awning cord, a handle for rotating said spindle, a ratchet wheel fixed on the spindle adjacent said handle, a pawl to prevent reverse rotation of said ratchet, and a support for said bracket bridging the corner of said frame.

Signed at New York in the county of New York and State of New York this 6th day of October A. D. 1926.

HENRY E. THOMPSON.
